Primary Examiner — John R Yeh(57) **CLAIM**

The ornamental design for a wireless presenter, as shown and described.

DESCRIPTION

- FIG. 1 is a front view of a wireless presenter, showing my new design;
 FIG. 2 is a rear view thereof;
 FIG. 3 is a left side view thereof;
 FIG. 4 is a right side view thereof;
 FIG. 5 is a top view thereof;
 FIG. 6 is a bottom view thereof;
 FIG. 7 is a front perspective view thereof; and,
 FIG. 8 is a rear perspective view thereof.

1 Claim, 8 Drawing Sheets(56)
